UNITED STATES PATENT OFFICE

ARTHUR GUY ENOCK, OF WEMBLEY PARK, ENGLAND, ASSIGNOR TO BURLECTAS
LIMITED, OF LONDON, ENGLAND

HANDLING OF BOTTLES AND CRATES IN BOTTLE-WASHING MACHINES

Application filed April 24, 1928, Serial No. 272,420, and in Great Britain May 7, 1927.

The present invention relates to handling of bottles and crates in bottle washing machines and is designed to provide means by which the dirty bottles and crates are inverted mouth downwards for cleansing purposes, passed through the washing machines and then returned to the mouth upward position without the bottles leaving the crates and with the object of passing the crates and bottles along in their passage through the dairy so that without extra handling they may proceed to the filling and capping machines in a clean condition and mouth upward.

The objects of the invention are to save labour and breakage of bottles and to permit of the crates and bottles when they are too hot for handling on leaving the sterilizing jets to be passed on direct to the filling machines.

The apparatus for carrying out the invention comprises a roller feeding path or conveyor upon which the crates of dirty bottles with mouths upward are placed, a crate inverting cradle or cage into which they are pushed, a bottle washing machine with washing and sterilizing jets, through which the bottles travel mouth downward and a re-inverting cradle or cage where they are turned mouth upward from which they travel onward to the track which leads to the filling machine, a loose or separate grid or cover being placed upon the top of the crate before entering the rotary inverter which with the crate is inverted and forms a support for the bottles in their passage through the washing machine.

The invention will be fully described by and with reference to the accompanying drawings and the further following details:-

Fig. 1. is a longitudinal section through a "tunnel" bottle washing and sterilizing machine showing the feeding conveyor, the inverter and re-inverter, and a mechanical method for feeding on, taking off and returning the grids to the feeding end of washer.

Fig. 2. is a diagram of one form of grid for use in the machine shown in Fig. 1.

Fig. 3. is an enlarged sectional elevation of

mechanism for placing the grids on the top of the crates at the feed end of machine.

Fig. 4. is an enlarged side elevation of mechanism for removing the grids.

Fig. 5. is a longitudinal section through a "tunnel" bottle washing and sterilizing machine showing the inverter and re-inverter and moving flexible wires, or chain grids or partial grids and dead plates by which the bottles are retained, in inverted crates.

Fig. 6. is a diagram of one form of chain grid, for use in machine shown in Fig. 5 composed of transverse wires or rods stretched between two chains.

Fig. 7. is a diagram of another form of grid for use in machine shown in Fig. 5 composed of a series of transverse rods and links.

Fig. 8. is an end view of another form of series of grids with a sprocket for use in the machine shown in Fig. 5 composed of a series of grids hinged together each of which is approximately the width of a crate.

Fig. 9. is a longitudinal section through a "tunnel" bottle washing machine showing the bottles retained in the inverted crates by continuous stationary grids.

Fig. 10. is an end view of Fig. 9 omitting the feeding conveyor, fitted with floor plates for inverting crates without loose grids.

Fig. 11. is a cross section on line 11-11 of Fig. 9.

Fig. 12. is a plan of part of Fig. 9.

Fig. 13. is an elevation of a mechanically operated inverter, fitted with floor plates for inverting crates without loose grids.

Fig. 14. is a plan of Fig. 13.

Fig. 15. is a side elevation of another method of engaging the inverter gear by the weight of the crate and bottles.

The apparatus comprises a "tunnel" bottle washing and sterilizing apparatus A of known construction with jets (not shown) by which water cleaning solutions and/or steam and/or air is injected into and around bottles in an inverted position, a crate inverter B and B¹ at each end of the tunnel by which crates D containing bottles can be inverted and reinverted, and means or mechanism by which the bottles can be retained in the crates in an inverted position without obstruction.

to the free flow of the jets while the crates are traversed through the washing apparatus.

The inverters B, B¹ are in the form of a cradle which may be rotated by hand or by mechanical means and may be constructed with metal frames *a* shown as welded angle iron rings secured together by crate guides C¹, carried by wheels or rollers *e* suitably mounted upon a frame *f* affixed to any suitable part of the bottle washing machine A so as to maintain its position relative thereto, and may be revolved by hand or by gears, cranks, links, eccentrics, cams, belts, chains or the like, or by a rack and pinion as shown in Figs. 13 and 14. Platforms or floor plates C extend between the crate guides C¹.

Guide and supporting bars *a'* are affixed to the upper edges of the washing tanks with rollers *a'* to support the crates D in their passage therethrough, the rollers *a'* being positioned at a level to come exactly opposite the guide plates C¹ in the inverter cradles. At the feed end of the machine a table conveyor D¹ with rollers *d'* is fitted to receive the full crates D of dirty bottles and at the delivery end of the machine a similar conveyor D² with rollers *d'* to receive the re-inverted crates with the washed bottles from the inverter B¹.

The crates are pushed forward into the apparatus by a travelling band D³ intermittently driven and each crate D is provided with slacking irons, lugs or projections *d* on their upper edges.

In the construction shown in Figs. 1 to 4, on the top of each crate before inversion, a grid E is placed to retain the bottles in the crate when inverted. The grids E may be placed upon the crates and removed therefrom by hand but it is preferred to do so by mechanical means as shown. The grids are placed in a receptacle F mounted over the conveyor D¹ with an inclined bottom with a slot at one edge (see Fig. 3) through which the grid E projects, lugs *d* of the oncoming crate engaging with it and drawing it down upon the top of the crate. An endless conveyor band F¹ is mounted on rollers above the machine with hooks f¹ (see Fig. 4) which engage the grids E at the delivery end of the machine, lift them from the crates and convey them back and deliver them into the receptacle F.

As the crate moves forward at the delivery end of the machine two projecting lugs e¹ shown in detail on the grid E, Fig. 2, slide up the inclined rails e² shown adjacent to grid E in Fig. 4. One of these rails e² is situated at each side of the conveyor F¹ and the loose grids E slide up these rails upon the projecting lugs until they are picked up by projecting hooks f¹, Fig. 4 on the conveyor F¹. The grids E are thus suspended from the conveyor and then taken off by the inclined rails or plate e³ shown at the feeding end of the ma-

chine in Fig. 3. They then gravitate into the receptacle F shown in the same figure.

In the construction shown in Figs. 5 to 8 the separate retaining grids E are dispensed with and a grid conveyor G is mounted over the washing troughs A on a level with the guide plates C¹ in the inverter cradles to retain the bottles in the inverted crate while being washed and sterilized. Dead plates g are fitted to direct the bottles on to and off the grid conveyor G. The grid conveyor G may be constructed with transverse rods connected to chains at their ends as in Fig. 6 or with transverse rods connected together by links as in Fig. 7 or it may be in the form of grids G¹ (similar to E Fig. 2) hinged or jointed together and passing over flat sided rollers as in Fig. 8. The conveyor grids will move at a speed synchronized with the table conveyor D¹ the crates resting upon the rollers a² and the bottle mouths on the grid conveyor G or G¹.

In the construction shown in Figs. 9 to 12, a fixed grid G² is fitted over the washing troughs on a level with the guide plates C¹ and platforms C in the inverter cradles to support the bottles and retain them in the inverted crates while being washed. The fixed grid extends the full length of the washing machine A and comprises a number of longitudinal rods supported on transverse bars.

In the construction shown in Figs. 13 to 15, the crate inverter B is rotated by a rack H, wheels h, h¹ and toothed rim h². The rack H is operated by the crank K and links l for a greater distance than its length so that during the period it is disengaged from the pinion h there is time for the next crate to be pushed into the cradle of the inverter.

As shown in Fig. 14, the rack pinion h is adapted to slide to and fro on its spindle and is drawn out of engagement with the rack by a spring h⁵ and pushed into engagement by pusher rod h⁴ and cranked lever h³. As each crate is brought up on the conveyor D¹ it pushes the rod h⁴ back and sets the inverter in motion and the crate is pushed into the cradle when the rotation stops.

Instead of the push rod h⁴, the rack mechanism may be operated by the depression of the end of the conveyor D¹ by the weight of the crate (see Fig. 15). The conveyor end is hinged at d⁴ and connected by a link d⁵ to the cranked lever h³ which controls the rack pinion h as above described.

A spring stop M may be employed to hold the inverted cradle either in its upright or inverted position.

The grids E whether separate, movable or stationary may be made tubular or of bars or rods of steel, aluminum, brass or bronze or other metal having sufficient stability and smoothness to allow the bottles to travel along mouth downward upon them without undue friction and vibration. The wires, tubes or

bars may be inserted into cross members and welded or otherwise secured thereto. These cross members are so arranged that while the sides or ends of the crate are travelling upon the rollers a^2 spaced is left in which the stacking iron of the crate may pass through without fouling either the rollers or the cross members.

Plenty of room is left between the longitudinal and transverse members of the grid and they are so disposed as to leave plenty of room for the jets of water, solution, steam or air employed for washing, cleansing and sterilizing the bottles and crates.

Where crates of bottles are required to leave the machine in a cool condition, cooling appliances may be provided in front of the reinverter.

In operation the crates D of empty, dirty bottles are placed in succession upon the table conveyor D¹ and moved forward one at a time into the cradle of rotary inverter or tippler B and the crate and bottles are inverted therein, the bottles being maintained in position either by the loose grids E or by the floor plates C across the cradle of the inverter upon which the mouths of the bottles rest when inverted.

The next on-coming crate from the feeding conveyor D¹ pushes the first crate D out of the inverter B with its bottles mouth downward into the washing machine where the crate comes to rest for a pre-determined period. The inverter B then makes another semi-rotation and a third crate is pushed in and moves the preceding two crates onward, this process being continually repeated while the machine is at work. When the column of crates reaches the reinverter B¹ the first crate is pushed into it and the operation goes on continuously in the same manner as described for the inverter. On or after leaving the reinverter the grid E is either picked up by hand and returned to the feeding end of the machine or is taken off and collected therefrom by the automatic conveyor, Fig. 1 which returns it to the feeding end of the machine and stacks it in the receptacle F. In the case of moving grids or stationary grids the bottle mouths rest on these and they are left in the washing machine as the crates are passed forward.

It should be noted that in the known types of tunnel bottle washing machines, the crates travel though not inverted with the stacking irons or lugs d upward the bottles being inverted by hand in the crates before entering the cleaning machine and being discharged or re-inverted by other means outside the washing machine. In this invention, however, I provide for the crates passing through the washing machine inverted with the stack-irons downward and either shrouding the irons in a loose grid (Figs. 1 and 2) or by providing spaces from end to end of

the machine to allow the stacking irons to clear both in the inverters and over the jets while at the same time guiding the crates so that they accurately retain their position in their passage through the washing machine and inverters.

What I claim as my invention and desire to protect by Letters Patent is:—

1. Apparatus for washing and sterilizing bottles in crates comprising a rotary inverter at the feed end of the machine to invert the crate and bottles carried therein, a wash-chamber through which the inverted crate and bottles are traversed, jet means therein, grids upon which the mouths of the inverted bottles rest and travel above the level of the jet means, guides extending longitudinally through the wash chamber upon which the inverted crates rest and travel, and a second rotary inverter at the delivery end of the machine to re-invert the crate and bottles, the rotary inverters both rotating about an axis longitudinal of the machine and in line with the direction of traverse of the crates and bottles.

2. Apparatus for washing and sterilizing bottles as in claim 1 constructed with a conveyor to feed the crates and bottles to the feed rotary inverter and with a roller table to carry the crates and bottles from the delivery rotary inverter.

3. Apparatus for washing and sterilizing bottles in crates comprising a rotary inverter at the feed end rotating about an axis longitudinal of the machine to invert the crate and bottles therein, grids formed of a plurality of rods upon which the mouths of the inverted bottles rest and travel, platforms and guides in the inverter between which the crate and bottles pass, a wash-chamber to receive the crate and bottles in the inverted position from the inverter, jet means therein, guides to carry the inverted crates and grids, the guides being arranged in the wash-chamber above the level of the jet means and a second rotary inverter, similar to the first inverter to re-invert the crate and bottles at the delivery end, the inverters and wash-trough being disposed in a horizontal straight line to give the crate and bottles a horizontal straight line passage through the apparatus.

4. Apparatus for washing and sterilizing bottles in crates comprising a rotary inverter at the feed end to invert the crate and bottles therein, grids upon which the inverted mouths of the bottles rest and travel, platforms and guides in the inverter between which the crate and bottles pass, a wash chamber to receive the crate and bottles in the inverted position from the inverter, jet means therein, guides in the wash chamber above the level of the jet means to carry the inverted crate and grids, and a second rotary inverter similar to the first inverter to re-invert the crate and bottles at the delivery

end, the inverters rotating about an axis longitudinal of the machine, and the wash chamber being disposed in a horizontal straight line to give the crate and bottles a horizontal straight line passage through the apparatus, mechanism by which a grid is fed to the crate as it enters the apparatus and by which said grid is removed from the crate as it emerges therefrom, and mechanism to rotate the crate inverters.

10 5. Apparatus for washing and sterilizing bottles in crates comprising, a rotary inverter at the feed end to invert the crate and bottles therein, grids upon which the inverted mouths 15 of the bottles rest and travel, platforms and guides in the inverter between which the crate and bottles pass, a wash-chamber to receive the crate and bottles in the inverted position from the inverter, jet means therein, 20 guides arranged in the wash chamber to carry the inverted crate, and grids and a second rotary inverter similar to the first inverter to re-invert the crate and bottles at the delivery end, the inverters and wash chamber 25 being disposed in a horizontal straight line to give the crate and bottles a horizontal straight line passage through the apparatus, and a travelling conveyor moving over the machine to lift the grid from the crate at 30 the delivery end and return it to the feed end of the machine and mechanism to rotate the crate inverters.

6. Apparatus for washing and sterilizing bottles in crates comprising a rotary inverter 35 open at both ends disposed at the feed end of the machine to invert the crate and bottles therein, platforms and guides in the inverter between which the crate and bottles pass, a wash chamber to receive the crate and bottles in the inverted position from the inverter, jet means therein, guides upon which the mouths 40 of the inverted bottles rest and travel above the level of the jet means and a second rotary inverter open at both ends similar to the first inverter to re-invert the crate and bottles at the delivery end, the inverters rotating about an axis longitudinal of the machine and being arranged with the wash-chamber in a 45 horizontal straight line to give the crate and bottles a horizontal straight line passage through the apparatus, mechanism to rotate the crate inverters and means by which such mechanism is set in motion by the presence of 50 the crate.

55 In testimony whereof I have hereunto set my hand.

ARTHUR GUY ENOCK.
